2,288,947

CONVERSION AND SEPARATION OF THE CONSTITUENTS OF ORGANIC MIXTURES CONTAINING BOTH FATTY AND RESIN ACIDS, PARTICULARLY TALL OIL

Frederick H. Gayer and Charles E. Fawkes, Chicago, Ill., assignors to Continental Research Corporation, Chicago Heights, Ill., a corporation of Illinois

No Drawing. Application July 17, 1939,
Serial No. 284,918

9 Claims. (Cl. 260—97.5)

This invention relates to a process for the separation of the major constituents of organic mixtures or oils containing both fatty and resin acids and especially to the clean, sharp and economic separation of the fatty and resin acids from such mixtures or oils, and particularly from tall oil. A more particular feature of our invention is the recovery of fatty and resin acids in the form of their commercially useful and valuable derivatives.

Tall oil is a by-product of sulphate pulp or kraft paper manufacture and is composed preponderantly of fatty acids, resin acids, unsaponifiable matter and coloring impurities. The unsaponifiable matter is composed of hydrocarbons and cyclic alcohols belonging to the group of phytosterols of which tall oil is an unusually rich source.

In our co-pending applications Serial No. 169,655 and No. 169,656 the latter now issued as Patent No. 2,223,850, both filed October 13, 1937, we have disclosed processes for the refining of crude tall oil and obtaining valuable by-products thereof. According to those applications we remove the coloring substances from crude tall oil and recover the commercially valuable phytosterol in a substantially quantitative yield and obtain a refined oil of light color and containing only a fraction of the unsaponifiable matter originally present. Crude tall oil also can be refined by distillation at reduced pressure. A greater portion of the fatty and resin acids and of the unsaponifiable matter distill over, the coloring matter and phytosterol remaining in the still residue. The tall oils refined by distillation are also of a considerably lighter color than the crude oil and also are essentially mixtures of fatty and resin acids with a rather high proportion of unsaponifiable matter.

Relatively little use has been made so far of crude or refined tall oil, as the simultaneous presence of both fatty and resin acids is of great disadvantage. These components in themselves, however, as fatty and resin acids respectively are of great commercial importance. A large number of useful compounds are derived from these acids and find innumerable industrial applications. A process which effects a sharp separation of the components of tall oil is, therefore, of great commercial value, especially in view of the vast potential supply of tall oil, resulting from the increasing importance of the sulphate process for paper making. According to the process of the present invention hereinafter set forth we not only effect a clean and sharp sep-

aration of the fatty and resin acid portion of tall oil but obtain as a result of that separation derivatives of fatty and resin acids respectively, commercially more valuable than either fatty or resin acids in themselves.

Numerous processes have been prepared relating to the separation of the components of tall oil, and one such process is disclosed in our co-pending application Serial No. 169,654 now issued as Patent No. 2,166,812, which deals with the separation of the fatty and resin acids by a process involving esterification of the fatty acids, neutralization of the resin acids with an alkali metal base and separating the fatty acid esters from the resin acid soaps by means comprising furfural and water and whereby we obtain as final products fatty acid esters and after acidifying the resin acid soaps, the free resin acids.

In distinction from our aforementioned process the present invention comprises esterification of the fatty acids, converting the resin acids into their aluminum salts and separating the fatty acid esters from the aluminum resinate. By this process we obtain high grade fatty acid esters and aluminum resinate, both products of considerably greater commercial value than either tall oil or fatty and resin acids in themselves.

In the present process, as in Serial No. 169,654, our Patent No. 2,166,812, we have taken advantage of the fact that the fatty acids in tall oil may be readily esterified with monohydric, aliphatic alcohols, such as methyl-, ethyl- or higher alcohols, whereas, given the proper conditions, the resin acids remain unchanged. This known chemical principle has been made the basis of a new and useful process of separation and is an integral part thereof, as hereinafter set forth. That is, the essence of this invention resides in taking together the old process of selective esterification of the fatty acid components carried out under controlled and specified conditions in combination with the new step of converting the resin acids into their aluminum salts and separating the fatty acid esters from the aluminum resinate by one of several possible methods.

The first step of our process is the esterification of the fatty acids contained in tall oil, which may be effected by several methods, such as refluxing or otherwise reacting the tall oil with a monohydric alcohol, such as methyl- or ethyl alcohol, or a higher monohydric alcohol. The alcohol is preferably used in excess over that required for the quantitative esterification of the fatty acids. Esterification can be effected at or below the boiling point of the alcohol used in

the presence of catalysts, such as, for example, sulphuric acid, or by any other conventional or suitable method. We prefer the esterification method disclosed in our co-pending application Serial No. 284,915, filed July 17, 1939, whereby esterification is effected in the absence of a catalyst at higher than atmospheric pressure. Esterification according to this method produces a mixture of fatty acid esters, resin acids, unsaponifiable matter, excess alcohol and the water formed in the esterification reaction. We then distill off the excess alcohol and the water and obtain a mixture consisting of fatty acid esters, resin acids and a minor portion of unsaponifiable matter.

The next step in our process comprises the conversion of the resin acids contained in this mixture into aluminum resinate. We achieve this conversion by what is ordinarily known in the art as precipitation, namely, neutralizing the resin acids contained in the esterified mixture with an alkali metal base, such as for instance, sodium hydroxide, and converting the alkali resinate into aluminum resinate by reacting them with a solution of an aluminum salt, such as for instance, aluminum chloride or sulphate. For example, we neutralize the acidity of the esterified mixture with the required quantity of a one-half to one normal solution of sodium hydroxide in water and pour the resulting mixture into somewhat more than the calculated amount of a 0.2 to 0.4 normal aluminum sulphate solution while the mixture is rapidly stirred. There results on the surface of the aqueous layer a 30 pasty or oily layer composed of fatty acid esters and aluminum resinate. Heating of the mixture now causes dehydration of the top layer and subsequent draining of the aqueous layer leaves a crust of a mixture of fatty acid esters and aluminum resinate. This mixture has the consistency of a soft solid with an oily touch, being essentially a mixture of a solid (aluminum resinate) with an oily liquid (fatty acid esters).

We obtain substantially the same result if instead of reacting the sodium resinate with an aluminum salt solution we react the mixture of fatty acid esters and resin acids with freshly precipitated aluminum hydroxide suspended in water. On continued shaking or stirring all the resin acids are converted into aluminum resinate. Heating the mixture and separating the solid from the water gives the same mixture as that obtained by the first method. The reaction with aluminum hydroxide, however, has the advantage that the volumes of reactants can be kept much smaller than in the case of precipitation.

The final step of our process consists of the separation of this mixture into fatty acid esters and aluminum resinate. We have found solvent extraction a convenient method for achieving this separation. By extracting the mixture with solvents which dissolve the fatty acid esters but are substantially non-solvents for the aluminum resinate, such as low molecular weight aliphatic alcohols, for example, methyl-, ethyl- or isopropyl alcohol, we obtain the aluminum resinate entirely free from esters. For instance, the major portion of methyl alcohol which at ordinary temperatures is a poor solvent for the fatty acid esters of tall oil becomes miscible with these esters in all proportions if the temperature is raised above the critical solution temperature, which in this case is 33° C. It has, however, substantially no solvent power for the aluminum

resinate and only such a quantity of aluminum resinate will be dissolved as will be carried along with the esters. The slight tendency of alcohols, especially manifest in the presence of small quantities of water, to decompose aluminum resinate into free resin acids and alumina can be reduced to a low figure by discontinuing the extraction at the point where all the esters are removed from the surface of the aluminum resinate.

For the extraction we use an extraction apparatus of the Soxhlet type. We obtain as extraction residue aluminum resinate which, after driving off the solvent, disintegrate into a fine white powder, and a liquid extract which contains a small quantity of aluminum resinate and some free resin acids which are easily removed from the esters by an alkali wash. Distillation of the esters yields high grade fatty acid esters of light color.

The following example will illustrate our process, although we do not limit ourselves to the conditions as disclosed in this particular example.

Example

The fatty acids contained in a refined tall oil, are esterified with methyl alcohol. Three and one-half kilograms of the esterified mixture are stirred into a quantity of 0.7 normal aqueous sodium hydroxide solution sufficient to neutralize the resin acids. The resulting ester-soap mixture is slowly poured and stirred into an approximately one-third normal solution of aluminum sulphate present slightly in excess over that required to react with the resin acid soaps. Heating of the reaction mixture causes it to solidify and float on the surface of the aqueous layer. After washing with 10 liters of neutral water the mixture is centrifuged to remove occluded water. The dry mixture is now extracted with methyl alcohol. We obtain 1.05 kilograms of aluminum resinate as a fine white powder and 2.40 kilograms of a yellow oil which after exhaustive washing with a dilute sodium hydroxide solution is distilled at reduced pressure. We obtain 2.0 kilograms of pale yellow fatty acid esters.

We claim as our invention:

1. The process of separating fatty acids from resin acids contained in tall oil, which comprises converting the fatty acids into their alkyl esters, converting the resin acids into their aluminum salts and separating the alkyl esters of the fatty acids from the aluminum resinate.

2. The process of separating fatty acids from resin acids contained in tall oil, which comprises converting the fatty acids into their alkyl esters, converting the resin acids into their aluminum salts and separating the fatty esters from the aluminum salts by extraction with a solvent which is substantially a non-solvent for aluminum resinate.

3. The process of separating fatty acids from resin acids contained in tall oil, comprising reacting the tall oil with a monohydric aliphatic alcohol to esterify the fatty acids, converting the resin acids into their aluminum salts and separating the fatty acid esters from the aluminum resinate.

4. The process of separating fatty acids from resin acids contained in tall oil, which comprises converting the fatty acids into their alkyl esters, reacting the resultant mixture with a suspension of aluminum hydroxide in water to convert the resin acids into their aluminum salts.

removing the water and separating the fatty acid esters from the aluminum resinate.

5. The process of separating fatty acids from resin acids contained in tall oil, which comprises converting the fatty acids into their alkyl esters, neutralizing the resin acids with aqueous alkali, reacting the mixture with a solution of an aluminum salt to convert the alkali resinate into aluminum resinate, removing the water and separating the fatty acid esters from the aluminum resinate.

6. The process of separating tall oil into fatty acids and resin acids, which comprises converting the fatty acids into their alkyl esters, converting the resin acids into their aluminum resinate and extracting the fatty acid esters with a volatile solvent which is substantially a non-solvent for aluminum resinate, removing the solvent and recovering the fatty acid esters.

7. The process of separating tall oil into fatty acids and resin acids, which comprises converting the fatty acids into their alkyl esters, converting the resin acids into their aluminum res-

inates and extracting the fatty acid esters with a volatile solvent which is substantially a non-solvent for aluminum resinate, removing the solvent and purifying the fatty acid esters by washing with an alkali solution and distilling.

8. The process of separating tall oil into fatty acids and resin acids, which comprises converting the fatty acids into their alkyl esters, converting the resin acids into their aluminum resinate and extracting the fatty acid esters with a low molecular weight aliphatic alcohol at a temperature above their critical solution temperature, removing the solvent by distillation and recovering the fatty acid esters.

10 15 9. In a process of separating tall oil into fatty acids and resin acids, the step which comprises converting the tall oil into a mixture of alkyl esters of fatty acids with aluminum resinate by esterifying first the fatty acids with a monohydric aliphatic alcohol and subsequently converting the resin acids into aluminum resinate.
